2,055,268

TRANSPORTATION SEAT

Clarence A. Van Derveer, Michigan City, Ind., assignor to S. Karpen & Bros., Chicago, Ill., a corporation of West Virginia

Application May 31, 1934, Serial No. 728,412

5 Claims. (Cl. 155—96)

This invention relates particularly to a transportation seat adapted for use in railway coaches and buses, although the invention may be employed elsewhere.

5 The primary object is to provide an improved seat of simplified construction which may be reversed in any direction, and which, in the operation of reversing the seat, will be laterally shifted. A further object is to provide an improved 10 seat which is securely anchored against rocking in its several positions, and in which automatic means are provided for tilting the foot-rest. The invention also contemplates means for adjusting the hinged back etc. Other specific objects and 15 advantages will appear as the specification proceeds.

The invention is illustrated, in a preferred embodiment, by the accompanying drawings, in which—

20 Figure 1 is a front view in elevation of a seat embodying my invention; Fig. 2, a sectional view, the section being taken as indicated at line 2 of Fig. 1; Fig. 3, a broken plan view of the base of the seat; Fig. 4, a plan view similar to Fig. 3 but 25 showing the seat frame rotated to a position at right angles to the base; Fig. 5, a longitudinal sectional view, the section being taken as indicated at line 5 of Fig. 3; and Fig. 6, a sectional view, the section being taken as indicated at line 30 6 of Fig. 3.

In the illustration given, A designates a base frame; B, a carriage or block slidably mounted on base A; C, a seat frame rotatably mounted on carriage B; and D, a seat structure carried by 35 the seat frame C.

The frame A may be of any suitable construction. As shown more clearly in Figs. 2 and 5, the frame A comprises two end pedestals or legs 10 which support at their tops the beams or track 40 members 11. The longitudinal beams 11 are provided on their inner sides with grooves 12 adapted to receive the rollers 13 which support the inner slidable block B, as shown more clearly in Fig. 2.

The pedestals 10 are apertured on their inner 45 sides to provide bearings 14 adapted to receive the foot-rest pivot shafts 15. Secured to the shafts 15 at their outer free ends are laterally extending bars 16 which support at their free 50 ends the foot-rests 17. Secured to one of the bars 16 is an upwardly extending finger 18 which is preferably inwardly turned at 19 as shown more 55 clearly in Fig. 5. Finger 18 is adapted to be engaged, as will be later described, by an abutment carried by the rotatable seat frame so as to throw

the foot-rest to the proper position automatically when the seat is reversed.

The carriage or slidable block B is equipped, as has been described, with laterally extending rollers 13 which are received within the grooves 12 5 provided by the track members 11.

The seat frame C is rotatably mounted upon the sliding carriage B. Frame C includes a seat plate 20 which is provided with an annular flange 21 extending within the collar 22 provided by the 10 carriage B. A locking ring 23 is secured to the flange 22 by bolts 24 whereby the seat plate 20 is secured to block B. As shown more clearly in Fig. 5, the carriage B is preferably provided with concentric bearing rings 25 and 26 which engage 15 the seat plate 20 and prevent its tilting. The seat plate 20 is provided at its corners with lateral extensions 27 which are secured to the tubular beams 28 of the frame by means of angle iron flanges 29. The vertical walls of the angle iron 20 flanges 29 are preferably spot-welded to the tubular frame members 28 while the horizontal flanges are bolted to the lateral extensions 27 of plate 20 by bolts 30.

The tubular frame members 28 are secured at 25 their ends to the tubular arm-rest frames 31 by spot-welding or other suitable means. The frames 31 have the somewhat rectangular or irregular shape shown more clearly in Fig. 2. The tubular seat frame members 28 are preferably 30 reinforced by a central tubular transverse beam 32. The rear tubes 33 of the arm-rest frames 31 are connected near their bottoms by two parallel tubular members 34 and 35. Preferably, the members 34 and 35 are buttressed by a support 35 member 36 which is spot-welded to the rear beam 28 and also spot-welded to the members 34 and 35 as shown more clearly in Figs. 3 and 5.

In order to support the seat frame rigidly upon the base, I prefer to equip the tubular beams 28 40 with legs or supports 37, as shown more clearly in Fig. 2, which are adapted to rest upon the track members 11 when the seat frame is brought into longitudinal alignment with the base structure.

I have also provided means for automatically 45 tilting the foot-rests so that when the seat is shifted, each foot-rest is also tilted into the proper position. As shown more clearly in Fig. 3, the tubular frame members 28 are connected near their ends by cross-straps 38. The straps 38 have 50 depending lugs 39 stuck therefrom and extending downwardly to such a distance as to engage the finger 18, as shown more clearly in Fig. 5. As the seat frame is rotated in one direction, the depending lug 39 at one end of the frame strikes the 55

upright finger 18 and swings it in one direction. As the seat is swung to the opposite position, the other depending lug 39 engages the opposite side of finger 18 and swings it to its opposite extreme position. By this means, the tubular rests 17 are swung to a desired position with respect to the seat structure, as shown more clearly in Fig. 2. It will be noted that, as shown in Fig. 2, the foot-rest 17 at the rear of the seat is disposed at a position where it serves as a foot-rest, while the opposite foot-rest 17 is raised to an inoperative position below the seat frame structure D.

Any suitable locking mechanism for securing the seat frame against rotation may be employed. 15 In the illustration given, the tubular frame members 28 are connected near their ends by cross straps 40 which are centrally apertured to provide locking openings 41. A spring-pressed plunger is housed within a recess 43 provided by frame A. 20 The plunger 42 is preferably equipped at its lower end with a treadle member 44 by which the plunger 42 can be pressed downwardly to free it from engagement with the locking opening 41.

In order to further buttress the seat frame C against rocking, I prefer to equip each of the plates 40 with an inwardly turned tongue 45 which is adapted to engage, as shown more clearly in Fig. 5, a vertical lug 46 carried by the frame A. The lug 46 has a horizontal terminal portion 47 which frictionally engages the tongue 45 as the seat frame is brought into the position shown in Fig. 5.

The seats are preferably provided with adjustable backs 48 which are hingedly mounted upon the tubular member 34 as shown in dotted lines in Fig. 2. Secured to each back at its side adjacent the arm-rest is a rod 49. The rod 49 is connected to a shifting bar 50 which is provided with a downwardly extending arm 51 connected by a tension spring 52 to the attachment 53. The tension of spring 52 tends to draw the back 48 toward its forward position. The forward end of bar 50 is provided with a series of notches 54 adapted to be engaged by a tooth 55 which is fixed to the arm frame. The bar 50 is provided with an adjustable screw stop 56 adapted to engage the abutment 57 of the frame to limit the forward movement of bar 50 and thereby the seat back 48. The forward end of bar 50 is connected by link 58 with a crank arm 59 pivotally secured to the frame at 60. The forward end of the crank arm 59 is curved to provide a handle 61 which extends within an open portion of the arm-rest, where it may be grasped by the occupant of the chair. 55 A spring 62 normally draws the rear portion of crank arm 59 toward the upper portion of the frame.

Resting upon the seat frame C are suitable spring cushion seats 63. Also, arm cushions 31^a 60 may be provided for the arm-rest frame 31 and secured to the top portion thereof, as shown more clearly in Fig. 2.

Any suitable means may be provided for shifting the sliding block or carriage B laterally on the base A when the seat frame is rotated. In the illustration given, a strap or link 64 is pivotally secured at one end of the base frame A, as shown in Fig. 4, and at the other end to one of the bolts 24, as shown more clearly in Fig. 6.

70 In the operation of the seat, the base structure A is preferably so arranged within the coach or bus that the side of the base equipped with the lock 42 is toward the aisle, while the opposite end of the base is toward the wall. When it is desired to reverse the direction of the seat, the

operator presses down the treadle member 44 to release the plunger 42 from locking engagement with the recess 44 of plate 40 carried by the seat frame C. The seat is then turned in the direction of the arrows, as shown in Fig. 4, the link 64 5 forcing the sliding block B to move away from the wall so that the seat frame clears the wall in the turning movement. As the seat frame is moved further in the direction of the arrows, the link 64 tends to move to a point diametrically opposite to that shown in Fig. 3, and at the same time, drawing the carriage member B toward the wall. When the seat frame has swung into alignment with the base again, the plunger 42 enters the locking recess 41 which was formerly adjacent the wall. At the same time, the lip 45 carried by plate 40 engages the clamp 47 which is fixed to frame A and securely holds the frame C against tipping or rocking. The supports 37 carried by the tubular frame members 18 come 20 to rest upon the track members 11 and provide a rigid support for the seat frame. As the seat frame C is swung to the reverse position, the downwardly extending lug 39 which was formerly adjacent the wall now strikes the finger 18 and 25 tilts the foot-rest into proper position adjacent the rear wall of the seat.

In the operation of the hinged back 48, the occupant of the seat leans against the back 48 and draws the crank arm 61 upwardly to withdraw 30 the notched bar 50 from engagement with the tooth 55. The hinged back may then be pressed rearwardly or allowed to move forwardly until it has assumed the desired position. The crank 61 is then released and spring 62 draws the bar 35 50 upwardly to bring one of the notches 54 into engagement with tooth 55.

While I have shown specific means for producing the results described, it will be obvious that mechanical equivalents may be readily substituted without departing from the spirit of my invention. The foregoing detailed description has been given for clearness of understanding only, and no unnecessary limitations should be understood therefrom, but the appended claims should be construed as broadly as permissible, in view of the prior art.

I claim:

1. In a seat of the character set forth, a base providing longitudinal tracks, a carriage slidably mounted on said tracks, a seat frame rotatably mounted in a horizontal plane on said carriage, a foot-rest member pivotally supported on said base, and means carried by said foot-rest cooperating with means on said seat frame for 55 tilting said foot-rest into operative position when the seat frame is turned in one direction and into inoperative position when the seat frame is moved in the opposite direction.

2. In a seat of the character set forth, a base 60 providing longitudinal tracks, a carriage member slidably mounted on said tracks, a seat frame rotatably mounted on said carriage, a foot-rest device pivotally mounted on said base and having foot-rest arms extending on both sides of said 65 base, and means carried by said seat frame engageable with means on said foot-rest device actuating said device and rendering one of said arms operative and other inoperative alternately as the seat frame is rotated in opposite directions. 70

3. In a seat of the character set forth, a base, a seat frame rotatably mounted thereon, a foot-rest member pivotally supported on said base, and means carried by said foot-rest cooperating with means on said seat frame for tilting said 75

foot-rest into operative position when the seat frame is turned in one direction and into inoperative position when the seat frame is moved in the opposite direction.

5. In a seat of the character set forth, a base, a tiltable foot-rest device pivotably mounted on said base and equipped with laterally extending foot-rests, a seat frame rotatably mounted on said base, and means carried by said seat frame engageable with means on said foot-rest actuating said device and rendering one of said laterally extending foot-rests operative and the other inoperative alternately as the seat frame is rotated in opposite directions.
10. In a seat of the character set forth, a base, a foot-rest device pivotally mounted in said base to tilt about a horizontal axis and equipped with laterally extending foot-rests on opposite sides of said base, said foot-rest device being provided with an upwardly extending actuating finger, and a seat frame rotatably mounted on said base and equipped at its ends with depending lugs adapted respectively to be brought into engagement with said finger when said frame is rotated toward the right or toward the left to tilt said foot-rest device.

CLARENCE A. VAN DERVEER.
